CLAIM

The ornamental design for a portable electronic device with animated graphical user interface, as shown and described.

DESCRIPTION

FIG. 1 is a front view of a first image of a portable electronic device with animated graphical user interface showing our new design;

FIG. 2 is a front view of a second image thereof;

FIG. 3 is a front view of a third image thereof; and,

FIG. 4 is a front view of a fourth image thereof.

The appearance of the image transitions sequentially between images shown in FIGS. 1-4. The process or period in which one image transitions to another forms no part of the claimed design.

The outer perimeter broken lines depict a portable electronic device and form no part of the claimed design. The remaining broken lines depict portions of the animated graphical user interface and form no part of the claimed design.
